UNITED STATES PATENT OFFICE

FRANZ YOKEL, OF MERIDEN, CONNECTICUT, ASSIGNOR TO THE MERIDEN
BRONZE COMPANY, OF SAME PLACE.

DESIGN FOR A LAMP-FOUNT.

SPECIFICATION forming part of Design No. 23,276, dated May 15, 1894.

Application filed March 5, 1894. Serial No. 502,452. Term of patent 3½ years.

To all whom it may concern:

Be it known that I, FRANZ YOKEL, of Meriden, in the county of New Haven and State of Connecticut, have invented a new Design for a Holder for Lamp-Founts; and I do hereby declare the following, when taken in connection with the accompanying drawing and the letters of reference marked thereon, to be a full, clear, and exact description of the same, and which said drawing constitutes part of this specification, and represents a perspective view of a lamp-fount holder embodying my design.

This invention relates to a design for a holder for lamp-founts, and consists in the configuration and ornamentation as shown in the accompanying illustration.

In outline horizontally the holder A is circular in shape. Vertically the sides spring from the bottom center, curving outward, thence swelling upward and inward, with a flaring neck, and a circular lower ornament or pendant. The surface is ornamented with a series of open panels B, alternating with foliated scrolls C, springing from a rib at the

bottom, which separates the holder from the pendant. Above these scrolls and panels is a waving ribbon D, overlapped at intervals by scrolls E, and having springing from it elaborate scrolls F, alternating with shells inclosing fret-work G, the whole merging into a rib H at the neck, above which rises a similar scroll and fret ornamentation, forming the flaring neck of the holder. The ornamentation of the pendant consists of a similar arrangement of scrolls and frets, the whole being of that form of ornamentation known as roccoco, as shown in the accompanying illustration.

I claim—

The design for a holder for lamp-founts as herein shown and described.

In testimony whereof I have signed this specification in the presence of two subscribing witnesses.

FRANZ YOKEL.
